DESIGN FOR A PAPER CUP DISPENSER

Frederick G. Miller, Omaha, Nebr., assignor to Carpenter Paper Co., Omaha, Nebr., a corporation of Nebraska

Application April 3, 1937, Serial No. 68,547

Term of patent 14 years

To all whom it may concern:

Be it known that I, Frederick G. Miller, a citizen of the United States, residing at Omaha, Douglas County, Nebraska, have invented a new,
original, and ornamental Design for a Paper Cup Dispenser, of which the following is a specification, reference being had to the accompanying drawing, forming a part thereof, and in which:

Fig. 1 is a front view of a paper cup dispenser
showing my new design;

Fig. 2 is a side view thereof; and

Fig. 3 is a top plan view thereof.

I claim:

The ornamental design for a paper cup dispenser as shown.
